UNITED STATES PATENT OFFICE

2,327,520

REFRIGERATED PORTABLE BOTTLE VENDOR

Joseph E. Hagstrom and Olaf C. Olsen, Kansas City, Mo., assignors to C. Earl Hovey, Kansas City, Mo., as trustee

Original application October 25, 1940, Serial No. 362,734. Divided and this application March 17, 1941, Serial No. 383,754

4 Claims. (Cl. 62—91.5)

This invention relates to vending machines of the portable type wherein a small number of packages may be kept for refrigeration and from which said packages are removed, one at a time, and the salient object is the provision of such a vendor wherein is employed unique means for maintaining the temperature at a predetermined point; means for establishing necessary circulation within the machine without the employment of mechanical expedients; and a novel, replaceable element for carrying the cooling medium that is disposed centrally of the vendor and preferably circumscribed by the bottles or articles being cooled.

This application is a division of our application for Letters Patent covering Portable bottle vendor, filed October 25, 1940, Serial No. 362,734.

Details of structure and manner of making and installing an ice container constitute important aims of the invention and will appear during the course of the following specification, referring to the accompanying drawings wherein:

Fig. 1 is a fragmentary top plan view of a portable bottle vendor made to embody the present invention.

Fig. 2 is a vertical central sectional view through the vendor, taken on line II—II of Fig. 1.

Fig. 3 is a horizontal cross sectional view taken on line III—III of Fig. 2.

Fig. 4 is a fragmentary perspective view of the cooling medium container illustrating the preferred manner of constructing the same.

Fig. 5 is a similar view showing a container made to embody a modified form of the invention; and

Fig. 6 is a perspective sectional view of a cooling medium container usable in the portable vendor, such as illustrated and described in our co-pending application and embodying a still further modification of the invention.

While the refrigerating means contemplated by this invention might be introduced into any insulated article holding compartment, it has been found more useful when introduced into and made a part of a portable bottle vendor comprising an insulated case 12 made relatively small to contain bottles 14 arranged in an endless row below a circle described by a delivery opening 16 in the cover 18 of case 12 when said cover is rotated. Suitable mechanism, generally designated by the numeral 20, is employed for the purpose of confining movement of cover 18 to a time when a coin is introduced through slot 22. Lid 24 normally maintains delivery opening 16 in a closed condition and therefore, all of bottles 14

are completely encased and held in spaced apart positions by a rack 26.

Rack 26 is mounted upon false floor 28, having a well 30 formed centrally therein to receive the hereinafter described cooling medium container.

An innerliner 32 removably positioned within case 12 serves to maintain bottles 14, rack 26 and the cooling medium container in a unitary condition so that if desired, all of said parts may be simultaneously withdrawn and a new innerliner substituted.

It has been found that dry ice 34 is an effective cooling medium.

Where a case 12 contains from 12 to 14 bottles, containers such as illustrated in Figs. 4 to 6 inclusive are commercially practicable and a temperature of from 36° to 44° F. will be maintained for a sufficient period of time to have all of the bottles withdrawn from case 12 under normal commercial conditions.

The preferred manner of constructing the cooling medium container is shown in Fig. 4. This container 36 is mounted in well 30 on the axis of innerliner 32. This container has a base 38 formed of wood or insulating material that supports spaced apart sheet metal walls 40 and 42 between which insulating material 44 is packed. In this instance, inner wall 40 extends across the bottom of the container to form a floor 46 immediately above base 38.

A cover 48 removably secured to container 36 through the medium of bayonet slot structure 50 and gasket 52, positively seals the container and precludes the escape of gas from therein through the top of the container as the dry ice 34 sublimates. Stratification or any static condition that would be detrimental to the cooling action within case 12 is automatically overcome through

the employment of ducts 54 extending upwardly and outwardly through walls 40 and 42 near floor 46. These ducts 54 are relatively small in cross sectional area and therefore create a stream of gas under pressure that forces the gas outwardly and into the chamber formed within innerliner 32 in case 12. Bottles 14 therefore, are positioned in a compartment, the air in which is constantly moving to insure even refrigeration. Voids or static air pockets cannot be established within the case 12 and as bottles are withdrawn through delivery opening 16, a part of the gas within the bottle compartment is allowed to escape to further contribute to the effectiveness of the cooling structure.

The insulating base 38 precludes metal-to-

metal contact between walls 40 and 42 and either floor 28 or rack 26. No metal part of container 36 that is capable of heat transfer is in contact with any portion of case 12 or its component parts and therefore, the cooling of the bottle compartment is effectively accomplished without loss of cooling medium.

The form of container 56 illustrated in Fig. 6 is slightly different from that just described in that it has an open upper end, and the gas formed by sublimation of the dry ice, spills over the edge of container 56 at the top thereof. An even and desirable heat transfer is established throughout the entire length of container 56, however, because sheet metal walls 58 are brought together along four vertical lines to present a metal-to-metal relation capable of heat transfer laterally toward bottles 14 in the circumscribing path which skirts container 56.

Inner wall 58 is polygonal in cross sectional contour while outer wall 58 is circular and therefore, the vertical lines of contact between inner and outer walls are in spaced relation around a path which is substantially concentric to the path within which bottles 14 are located.

For the reasons above mentioned, with respect to container 36, the form of container 56 shown in Fig. 6 should have a base 60 of insulating material that may be pressed into well 30.

The form of container 62 illustrated in Fig. 5 comprises a base of wood or other insulating material 64 from one side of which extends inner and outer walls 66 and 68 respectively, having insulating material 70 packed therebetween. Inner wall 66 projects upwardly, outwardly and thence downwardly along the outer surface of outer wall 42 to present an uninterrupted sheet metal member that is capable of conducting heat units. Heat exchange between the air surrounding bottles 14 and the dry ice within container 62 therefore, is insured.

The length of downwardly projecting portion 72 of wall 66 may be varied to suit conditions for the longer this portion 72 is made, the greater the heat exchange will be. Either of the three forms of containers shown in Figs. 4, 5 and 6 is usable in case 12 and will adequately cool all bottles 14 therein.

Having thus described the invention, what is claimed as new and desired to be secured by Letters Patent is:

1. In a vending machine of the character described, a closed case; a floor within said case having a well formed therein; a rack for packaged goods on the floor surrounding the well; and a refrigerant container having a base seated in said well, said container having inner and outer metallic walls contiguous to each other at intervals along vertical lines to effect transfer of heat radially from the container toward said rack.
2. In a vending machine of the character described, a closed case; a floor within said case having a well formed therein; a rack for packaged goods surrounding the well; and a closed container for dry ice having a base seated in said well, said container having radial outlet ports near its base for escape of gas created through sublimation of the dry ice.
3. In a vending machine of the character described, a closed case; a floor within said case having a well formed therein; a rack for packaged goods surrounding the well; and a container for dry ice having a base of non-conducting material removably seated in said well; said container having spaced inner and outer metallic walls and insulation therebetween, the inner wall projecting outwardly and downwardly along a partial length of the outer wall for radial heat exchange between air surrounding the packaged goods and dry ice within said container.
4. In a vending machine of the character described, a closed case; a floor within said case having a well formed therein; a rack for packaged goods on the floor surrounding the well; and a refrigerant container having a base of non-conducting material seated in said well, said container having an inner metallic wall of angular cross section and an outer metallic wall of circular cross section in contiguous relation with angles of said inner wall to effect transfer of heat radially from the container.
